[57] CLAIM

The ornamental design for a frame for mirrors, as shown and described.

DESCRIPTION

FIG. 1 is a perspective view of a frame for mirrors showing my new design, the coarse and fine stippling indicating differences in texture between portions thereof;

FIG. 2 is a front elevational view thereof;

FIG. 3 is a top view thereof;

FIG. 4 is a bottom view thereof;

FIG. 5 is a side elevational view thereof, the opposite side being a mirror image;

FIG. 6 is a rear elevational view thereof; and,

FIG. 7 is an enlarged fragmentary sectional view taken along the line 7—7 in FIG. 6; the broken line showing of the mirror is for environmental purposes only and forms no part of the claimed design.
